UNITED STATES PATENT OFFICE.

PETER MULOCK, OF LEADVILLE, COLORADO.

GARMENT-SUPPORTER.

SPECIFICATION forming part of Letters Patent No. 761,982, dated June 7, 1904.
 Application filed August 4, 1903. Renewed May 5, 1904. Serial No. 206,577. (No model.)

To all whom it may concern:

Be it known that I, PETER MULOCK, a citizen of the United States, residing at Leadville, in the county of Lake and State of Colorado, am 5 the inventor of certain new and useful Improvements in Garment-Supporters, of which the following is a specification.

My invention relates to that class of garment-supporters having a buckle member 10 comprising a rim and a chape or shank upon which such rim is mounted having relatively movable side portions, each provided at one end with integral tongues and having at the opposite end a flexible hook connecting such 15 side portions and an eye member provided with an eye for receiving such hook.

It relates further and particularly to the combination of a shouldered flexible hook upon the chape or shank of a buckle with an 20 eye member having an eye narrower than the shouldered portion of the hook when in normal position, such eye member being provided with suitable means for attaching a button or buttons thereto.

25 The principal object of my invention is to provide a simple, economical, and efficient garment-supporter.

Another object is to provide a garment-supporter comprising an eye member with suitable means for attaching a button or buttons thereto.

Other and further objects of the invention will appear from an examination of the drawings and the following description and claims.

35 The invention consists in the features, combinations, and details of construction herein-after described and claimed.

In the accompanying drawings, Figure 1 is 40 a view in elevation of a pair of my improved garment-supporters in operative position in connection with the end webs of a pair of sus-

penders and showing the manner of connecting the suspenders with a pair of trousers; Fig. 2, a view in elevation of the buckle and eye members in their connected position; and Fig. 3, a perspective view showing the rim, hooked shank, and eye and button portions all separated from each other as they appear before being assembled.

45 In constructing a garment-supporter in ac-

cordance with my improvements I provide a buckle member comprising a rim *a*, and a shank comprising relatively movable integral side portions *b* and *c*, made of wire, and therefore flexible, each provided at one end with an integral tongue *d* and *e* in engagement with the rim and provided at the opposite end with an integral flexible hook *f*, having side shoulder portions *g* and *h*, all formed of one integral wire. These shoulder portions are normally 55 wider from outside to outside than the eye in which they are to be held, so that when inserted therethrough they yieldingly engage the eye, and thus prevent the accidental separation of the parts. The shank and hook being of one integral piece of spring-wire are 60 both flexible. This permits the shoulder portions of the hook to be compressed so as to pass through the eye when desired. The extreme end of the hook is tapered outward to 70 toward the shoulders, so as to cause the shoulders to be compressed by means of the sliding contact with the eye while the hook is passing therethrough into position.

The ends of the rim are each provided with 75 perforations *i* and *j*, adapted to receive the laterally-extending side portions *k* and *l* of the shank upon which the rim is pivotally mounted.

An eye member is provided, comprising an 80 eye portion *m* narrower than the shoulder portions of the hook above described when the hook is in its extended or normal position, but wide enough to admit such hook with its shoulders therethrough when the hook is compressed, such eye member being also provided with an integral elongated loop *n*, adapted to be mounted between the folds of a garment in connection with which it is to be used and attached to such garment by means of stitches 85 or rivets.

To provide suitable means for riveting the eye member to the garment upon which it is to be used, the elongated loop portion is made relatively narrow throughout substantially its 95 entire length, the extreme ends being enlarged so as to form eye portions *o* and *p* for receiving suitable rivets which may be of any ordinary and well-known type. The eye member is also provided at its central portion with a 100

- screw-threaded stem *q* and with a central loop or eye portion *r*, having a threaded central perforation *s* therethrough, such threaded perforation being adapted to receive the 5 screw-threaded stem *t* of a button *u*, which is mounted upon one side of the eye member for supporting the undergarments, and a second button *v* is provided having a central screw-threaded perforation *w*, adapted to be 10 mounted upon the threaded stem of the eye member so as to be in position to be used upon the opposite side of the garment for any desired purpose.

The button *v* when used upon a pair of 15 boy's trousers—for instance, in the manner illustrated in Fig. 1—is in position to have the waist buttoned thereto when it is desired to wear it outside of the suspenders.

I claim—

- 20 1. In a device of the class described, the combination of a buckle member comprising a rim, a shank upon which such rim is mounted having relatively movable side portions provided at one end with a flexible hook upon 25 and connecting such side portions, tongue mechanism mounted in engagement with the rim, and an eye member provided with an eye for receiving such hook, substantially as described.
- 30 2. In a device of the class described, the combination of a buckle member comprising a rim, a shank, upon which such rim is mounted having flexible side portions each provided at one end with an integral tongue in engagement with the rim, an integral flexible hook upon and connecting the opposite ends of such side portions, and an eye member provided with an eye for receiving such hook, substantially as described.
- 35 4. In a device of the class described, the combination of a buckle member comprising a rim, a shank upon which such rim is mounted having flexible side portions each provided at one end with an integral tongue in engagement with such rim, an integral flexible hook upon the opposite end of such side portions provided with side shoulders, and an eye member provided with an eye narrower than the shoulder portion of such hook, substantially as described.
- 40 5. In a device of the class described, the combination of a buckle member comprising a rim, a shank upon which such rim is mounted having relatively movable side portions each provided at one end with an integral tongue in engagement with such rim, an integral flexible hook upon the opposite end of such side portions provided with side shoulders, and an eye member provided with an eye narrower than the shoulder portion of such hook, substantially as described.
- 45 6. In a device of the class described, the combination of a buckle member comprising a rim, a shank upon which such rim is mounted having relatively movable side portions each provided at one end with an integral tongue in engagement with such rim, an integral flexible hook upon the opposite end of such side portions provided with side shoulders, and an eye member provided with an eye narrower than the shoulder portion of such hook, substantially as described.
- 50 7. In a device of the class described, the combination of a buckle member comprising a rim, a shank upon which such rim is mounted having relatively movable side portions each provided at one end with an integral tongue, a flexible hook upon the opposite ends of such side portions, an eye member provided with an eye for receiving such hook and having an integral loop portion provided with a screw-threaded stem and such eye member also having a central screw-threaded perforation therethrough, a button provided with a screw-threaded stem adapted to be mounted in such screw-threaded perforation on one side of the loop portion, and a button provided with a central screw-threaded perforation mounted upon the screw-threaded stem of such eye member, substantially as described.
- 55 8. In a device of the class described, the combination of a buckle member comprising a rim, a shank upon which such rim is mounted having relatively movable side portions each provided at one end with an integral

tongue, a flexible hook upon and connecting the opposite ends of such side portions, an eye member provided with an eye for receiving such hook and having an integral loop portion provided with a screw-threaded stem, 60 and a button provided with a screw-threaded axial perforation for receiving such stem, substantially as described.

9. In a device of the class described, the combination of a buckle member comprising 65 a rim and a shank having a hook thereon, an eye member provided with an eye for receiving such hook and having an integral loop portion provided with a screw-threaded stem, and a button provided with a screw-threaded 70 axial perforation for receiving such stem, substantially as described.

10. In a device of the class described, the combination of a buckle provided with a hook, 75 an eye member provided with an eye for receiving such hook and having an integral loop portion provided with a screw-threaded stem and such eye member also having a central screw-threaded perforation therethrough, a button provided with a screw-threaded stem 80 adapted to be mounted in such screw-threaded perforation on one side of the loop portion, and a button provided with a central screw-threaded perforation mounted upon the screw-threaded stem of such eye member, substantially 85 as described.

11. In a device of the class described, the combination of a buckle member comprising 90 a rim, a shank upon which such rim is mounted having relatively movable side portions each provided at one end with an integral tongue, a flexible hook upon the opposite ends of such side portions, an eye member provided with an eye for receiving such hook and having an integral loop portion provided with a 95 screw-threaded stem and such eye member also having a central screw-threaded perforation therethrough, a button provided with a screw-threaded stem adapted to be mounted in such screw-threaded perforation on one 100 side of the loop portion, and a button provided with a central screw-threaded perforation mounted upon the screw-threaded stem of such eye member, substantially as described.
